THOMAS A. REID, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC FURNACE RESISTOR.

BEST AVAILABLE COPY
Application filed June 25, 1921. Serial No. 480,262.

My invention relates to electric furnaces and particularly to electric-resistance furnaces and it has for its object to provide a relatively simple and easily installed resistor-supporting means for such furnaces.

In practicing my invention, I provide a plurality of supporting members, extending from the side walls of the furnace into the chamber, the supporting members being substantially of L-shape. I provide a plurality of notched refractory resistor-supporting bars located in oppositely spaced relation relatively to each other and wind a flat metallic resistor member between and over the two bars, the resistor member being located in the notches of the respective bars. One of the resistor-supporting bars is supported by a pair of upper supporting members extending from the furnace wall, the weight of the two notched bars and of the resistor member wound thereon, being carried by these two supporting members.

In the single sheet of drawings,

Figure 1 is a view, in lateral cross section on the line I—I of Fig. 2, of an electric-resistance furnace comprising the device embodying my invention and

Fig. 2 is a view in longitudinal vertical cross section on the line II—II of Fig. 1.

An electric-resistance furnace, comprising a metallic framework or casing 3, is provided with suitable supporting members 4. Bricks or blocks 5, of a suitable heat-insulating material, are located inside of the framework 3. Bricks or blocks 6, of a suitable high-temperature-resisting refractory material are located inside of the bricks 5 to form a furnace chamber 7.

A plurality of refractory supporting members 8, substantially of L-shape, are located in the inner side wall, formed by the bricks 6, and project into the furnace chamber 7. The members 8 are located in aligned spaced-apart relation both horizontally and vertically.

A plurality of heating elements 9, located in the furnace chamber 7, comprise an upper refractory bar 10 provided with a plurality of notches 11. While the lateral cross section of the bar 10 is preferably rectangular, it is desirable that the surface of the bar in the notches be rounded in order to cooperate with the flat metallic resistor member 12 which is located therein.

The resistor member 12 is wound in the

form of a flat helix, the upper end-connections of which are located in the notches 11 of the upper bar 10 while the lower end connections are located in notches of a second bar 10 which is located in oppositely spaced relation to the upper bar 10. The vertical height of the helix into which the resistor member 12 is formed is such that the lower bar 10 does not rest upon the lower set of supporting members 8. However, the vertically extending portion of the members 8 is in operative engagement with the bars 10, it being understood that the horizontal distance between the edges of the members 8 is slightly less than the length of the bar 10.

The ends of the respective resistor members 12 are located substantially at right angles to the plane of the helix and extend through the walls of the furnace, in a suitable insulating tube 13. Suitable contact terminals 14 may be provided at the outside of the furnace to permit of connecting the resistor members 12 in any desired combination relatively to each other or to suitable supply-circuit conductors (not shown).

The method of mounting the removable heating element comprising the two spaced bars 10 and the resistor member 12 wound thereon, is substantially as follows: it is assumed that the resistor member 12 has been wound in substantially the form illustrated in the drawings, so that the upper and lower bars 10 may be placed in their proper operative positions relatively thereto. The heating element may be supported by the operator by means of the upper bar 10, the heating element being held in the furnace chamber at such distance from the wall that the end of the resistor may be placed in the opening in the insulating tube 13, after which the heating element may be so moved toward the wall that the horizontally extending ends are fed through the insulating tubes 13. The upper bar 10 must be so raised as to pass over the small vertical extension of the upper side of the supporting members 8 until it has been moved close enough to the wall to permit of dropping it into substantially the position illustrated in Fig. 1. It is understood that the lower bar 10 has also been moved toward the wall and that it is moved to substantially the position illustrated in Fig. 1 at the same time that the upper bar 10 is so moved.

It may be noted that the device embodying my invention provides a heating element comprising only three parts, the weight of the heating element and of the lower bar being carried by the upper bar. The lower bar is effective mainly to insure that the lower part of the helix shall be maintained in its proper operative position, and is also effective to maintain the vertically extending portions of the helix in a taut condition during the operation of the furnace. As the metal used for the resistor is of a character adapted to withstand relatively high temperatures and has a relatively large coefficient of linear expansion, this provision for maintaining a ribbon resistor taut is an important element of my invention.

It may further be noted that, by the use of the device embodying my invention, I am able to so wind the resistor member that the flat surface of a ribbon is available for radiating the heat generated into the furnace chamber.

It may further be noted that the device embodying my invention provides a heating element for an electric-resistance furnace which may be easily and quickly installed or removed.

Various modifications may be made in the device embodying my invention without departing from the spirit and scope thereof, and I desire that only such limitations shall be placed thereon as are imposed by the prior art or are specifically set forth in the appended claims.

I claim as my invention:

1. An electric furnace comprising a plu-

rality of walls enclosing a furnace chamber, a plurality of aligned, spaced refractory members located in certain of said walls and extending into said chamber, a notched refractory bar supported by certain of said refractory members, a second notched refractory bar located in opposite parallel-spaced relation to said first bar and a metallic resistor helically wound around said two bars and supported in the notched portions of one of said bars.

2. An electric furnace comprising a plurality of walls enclosing a furnace chamber, a notched refractory bar supported in said chamber in spaced relation to said walls, a helically-wound resistor member supported in the notches of said bar and means engaging said resistor member for maintaining the lower portions of said resistor loops in spaced operative relation in said furnace chamber under all operating conditions.

3. An electric furnace comprising a plurality of refractory walls enclosing a furnace chamber, an elongated single member of refractory electric-insulating material supported in said chamber in spaced relation to one of said walls, a resistor member of substantially flattened helical-shape depending from said elongated member, and a second elongated single member, of refractory electric-insulating material, engaging the lower ends of the helices of said resistor member and supported thereby.

In testimony whereof, I have hereunto subscribed my name this 20th day of June, 1921.

THOMAS A. REID.
